FLOATING PRESSURE CAM

Julius E. Shafer, Chicago, Ill.

Application August 6, 1945, Serial No. 609,140

4 Claims. (Cl. 77—3.)

1

The present invention relates to a floating pressure cam and more particularly to a resiliently urged cam follower construction for maintaining accurate riding contact on a cam to control rocking of a tool carriage of a lathe for turning accurate profiles or contours.

There are in use at the present time lathes equipped with double former bars for controlling transverse or rocking motions of tool carriages on the lathes, but it has been found that it is difficult to secure extreme accuracy of adjustment without undue friction between the cams and the shoes of the cam followers.

The present invention makes possible the accurate adjustment of cams and cam shoes for assuring positive riding engagement of the shoes against cams fixed in one of the former bars by providing a floating pressure mounting for a follower cam in the other former bar.

An object of the present invention is to provide a floating pressure follower cam mounting which will maintain positive and uniform contact of a cam shoe with a cam without subjecting the cam to excessive wear.

Another object of the present invention is to provide a novel cam bar construction for double formers wherein different cams may be used in the same former bars thus reducing cost of special cams to a minimum.

A further object of the present invention is to provide a former bar construction for tool carriages of lathes wherein cams may be removably mounted, accurately adjusted lengthwise of the bar, and locked in adjusted position to facilitate accuracy of cooperation between the cams and the tool carriage of the lathe.

The invention has for an additional object the provision of means for adjustably mounting a cam in its former bar to secure accuracy of cooperation between the cam and the carriage arm by adjustment of the cam lengthwise of its bar.

A further object is to increase the accuracy of profile turning lathes having rocking tool or work carrying carriages while decreasing the cam setting time for such lathes.

Another and still further object of the present invention is to provide a former bar construction wherein cams used for controlling transverse carriage movements for turning one type of surface or profile may be quickly removed and replaced with cams for turning another type of surface or profile with minimum loss of time.

A still further object of the present invention is to provide a double former bar cam mounting

2

arrangement wherein extreme accuracy of control of transverse carriage movements is achieved.

An additional object of the present invention is to provide a floating pressure cam arrangement for causing positive engagement of a cam shoe against its cam regardless of the irregularity of the cam surface.

The objects of the present invention are achieved by the provision of a floating pressure mounting for the cam in the lower former bar which bears against the cam shoes with pressure sufficient to maintain positive contact of the shoes with the cam in the upper former bar, regardless of its contour, without imposing undue friction on the shoes and cams.

The above, other and further objects of the present invention will be apparent from the following description and the accompanying drawings.

20 An embodiment of the present invention is illustrated in the accompanying drawings and the views thereof are as follows:

Figure 1 is a front side elevational view of a lathe having a bracket applied thereto and equipped with former bars and cams of the present invention, showing the relationship of parts with the tool carriage part way along its range of travel.

Figure 2 is an enlarged transverse cross-sectional view taken along the line II—II of Figure 1 and showing, in end elevation, the tool carriage of the lathe, the cam shoes on the arm of the carriage, the former bar carriage, and the cam carrying former bars with the carriage arm in horizontal position.

Figure 3 is a fragmental end elevational view of the free end of the carriage arm, showing relative position of the cam shoes when the cam tilts the arm downwardly.

40 Figure 4 is a top plan view of the upper former bar.

Figure 5 is a top plan view of the lower former bar.

Figure 6 is an enlarged fragmentary side view, partly in longitudinal section and partly in elevation, of the upper and lower former bars of the present invention showing the bars equipped with double cams for oscillating the lathe carriage carrying a tool post with two cutting tools to make two successive cuts including a roughing cut and a finishing cut on the inside face of a pillow block for bearings and showing the spring pressure mounting for the lower cam.

As shown on the drawings:

55 A lathe is designated diagrammatically at A in

Figure 1 having a head stock 10 supporting and driving a work piece such as a pillow block 11. The lathe A has a carriage 12 adjustably carrying a tool holder 13, in the usual manner. The lathe has a longitudinal support post or bar 14 for the carriage.

Attached to the front side surface of the lathe is a bracket 15, generally rectangular in elevation and supporting an upper former bar B and a lower former bar C.

Referring to Figures 4 and 6, it will be noted that the former bar B is generally rectangular in shape, and has threaded holes 16 extending in from its top surface to receive bolts for suspending the bar from the top of the bracket 15. Substantially midway of its length and opening through the under surface of the bar is a rectangular recess 17 extending part way of the height of the bar terminating in shoulders 17a. Above the recess the bar is provided with an elongated slot 18 having a shouldered margin 19. The recess 17 of the upper former bar B affords a space in which cam means may be secured. Figure 6 shows two similar cams 20 and 21 having their cam surfaces 22 of the same contour. Cams 20 and 21 are separated by a shim 23 while a filler block 24 is inserted between the cam 21 and the adjacent end of the recess 17. The cams have threaded bores 25 and 26 to receive cap screws 27 and 28. The heads 29 and 30 of the screws rest on the shoulder or ledge 19 and when the screws are tightened into the cams they hold the cams tightly against the shoulders 17a.

In order to adjust the cams lengthwise of the former bar B the bar has a longitudinal bore 31 extending inwardly from one end thereof to the recess 17. The outer end of the bore 31 is threaded at 31a. A long bolt 32 is seated in the bore 31 to bear against the cam 20 and has a head 32a threaded into the threaded bore 31a, to adjust the bolt lengthwise of the former bar. With this adjustment, and the use of the shim 23 and filler block 24, it is apparent that the cams may be so positioned lengthwise of the bar as to be accurately adjusted with respect to the follower shoes on the arm of the carriage.

The bar B is provided with transverse apertures 33 through which suitable attaching bolts may be passed to engage the bracket 15, if desired.

The lower former bar C is likewise of elongated rectangular formation and is provided near its ends with longitudinally elongated slots 34 and 35 through which attaching bolts may be passed to fasten the bar to the frame 15. The provision of the elongated slots 34 and 35 is to enable endwise adjustment of the bar with respect to the bracket.

The bar C is formed with an open topped, closed bottom central recess 36, which is rectangular in side elevation and which extends the full width of the bar. A cradle 37 is fitted within the recess 36. This cradle is provided with a recess 38 in which the lower cam 39 is mounted. The cam 39 is fastened in the recess 38 of the cradle 37 by means of cap screws 40 entered through openings 41 in the bottom of the cradle and in threaded bores 42 in the cam. The cradle is counterbored at 43 to receive the heads of the screws. The confronting faces of the bottom of the recess 36 of the bar C and of the cradle 37 are provided with a plurality (four being shown) of registering bores 44 and 45 which when the parts are assembled contain springs 46 which tend to move the cradle upwardly with respect

to the recess. To limit upward movement of the cradle in its recess and to load the springs to the desired pressure, bolts 47 and 48 are entered through bores 49 and 50 in the cradle and are threaded into threaded bores 51 and 52, respectively, in the bar C. The upper ends of the bores 49 and 50 are counterbored at 53 and 54 to receive the heads of the bolts 47 and 48. Adjustment of the bolts 49 and 50 in the cradle, as before stated, adjustably loads the springs 46 and controls the level of the cradle relative to the bar C. Figure 6 shows two of the four springs 46 encircling the bolts 49 and 50.

It will thus be noted that a floating pressure mounting is provided for the lower cam 39 in the cradle 37.

The contour faces 22 of the upper cams 20 and 21 are convex, consequently the upper face of the lower cam 39 is formed with complementary concave faces 55 and 56 in register with the cams 20 and 21. The concave cams 55 and 56 are shown as separated by a ridge 57.

As shown in Figure 2, the tool carriage 12 is provided with a laterally projecting arm 58 disposed to travel between the upper and lower former bars B and C in the bracket 15. The outer end of the arm 58 is bifurcated to pivotally support upper cam shoe 59 and lower cam shoe 60. The shoes are pivoted to the end of the bar 58 by pins 61 and 62, respectively.

It will be noted in Figure 2 that the cam shoes 59 and 60 are of appreciable width to have relatively long lines of sliding contact on the wide confronting faces of the former bars and cams. These long transverse contact lines prevent the shoes from cocking and hold the shoes in vertical positions. As the arm 58 oscillates from its lowermost angular position to its uppermost angular position, the pins 61 and 62 swing in an arc and the shoes will be moved relatively to each other, sliding back and forth across the faces of the cams but the long contact lines of engagement with the cams will hold the shoes in true vertical positions.

The arcuate path of the pivot pins changes the vertical distance between the tilting centers of the shoes, and slightly changes the distance between the apices or cam-engaging faces 63 and 64 of the shoes. Thus as shown in Figure 2, the distance D between the apices of the shoes is greater, when the centers of pivots 61 and 62 are vertically aligned, than the distance D' shown in Figure 3, when the pivot centers are out of vertical alignment. Heretofore it has been necessary to set the riding clearance for the shoes on the cams when the pivot centers were in vertical alignment and the distance D was maximum. Such a setting, however, results in looseness or play between the shoes and cams when the distance D decreases. As a result, accurate profile cutting was not obtained. In the present invention, on the other hand, the spring mounting for the bottom cam accommodates changes in distance D and insures full riding contact of the shoes on the cams to prevent the heretofore-encountered looseness.

In setting the spring load on the follower cam of this invention, the bolts 47 and 48 are so positioned that spring pressure will be effective on the follower cam even when the distance D' is minimum. It will be noted from Figure 6 that the apices are rounded to reduce surface contact with the upper and lower cams.

Figure 6 shows a sectional view through a pillow block work piece 11, the interior surface of

which is to be given a truly spherical shape by the cutters mounted on the cutter bar 13. Two cutters 65 and 66 are mounted in tandem on the cutter bar 13. The first cutter 65 is to take a rough cut in the work piece 11, and the second cutter 66 is to make a finishing cut, in one advance of the carriage.

The cams 20 and 21 and 39 are designed to oscillate the carriage for transverse movement thereof in a manner to make the spherical cuts in the work piece 11 as described.

Figure 6 shows the first cutter 65 as having been moved through the work piece 11 and the second cutter 66 in cutting engagement with the interior surface of the same.

Figure 6 shows the cam shoes 59 and 60 against the high side of convexity of the first cam 21 and the low point of concavity of the lower cam 56 of the cam member 39.

It is to be understood that when the parts are arranged to begin initial movement of the carriage to the left, as viewed in Figures 1 and 6, the apices of the cam shoes will be at the extreme right (Figure 6) of the cams. As the carriage is advanced to the left, the shoes will move downwardly under the convexity of the face of the first cam 21 thus moving the first cutter 65 inwardly of the work piece to its maximum inward movement as determined by the high point of the cam 21. The carriage will then swing back as the shoes move into register with the shim 23 at which time the first cutter 65 is freed of engagement with the work piece and the second cutter is about to begin its operation. Continuation of the movement of the carriage to the left will cause the cam shoe to engage the second cam 20 and oscillate the carriage in a manner to direct the second cutter 66 along spherical lines to finish the surface of the work piece. When the carriage has reached its limit of movement to the left, mechanism (not shown) but well understood, becomes effective to shift the cutters away from the work piece and enable withdrawal of the carriage ready to machine another work piece 11.

It will be noted that because of the construction of the upper former B, cams may be readily applied to the recess 16 having contours to produce the desired surface in the work piece. It will be noted that it is unnecessary to remove the upper former bar B, all that has to be done is to release the screws 27 and 28 from engagement with the cams, and ease off the spindle bolt 32 whereupon the cams may be removed from the former bar. Other cams may then be installed, secured by the screws 27 and 28 and endwise adjusted by proper manipulation of the spindle bolt 32.

In like manner, the lower cam 39, having contour faces of complementary shape to the contours of the cams in the upper former bar may be applied to the recess 38 in the cradle 37 by removing the cradle from the lower work bar C and then moving the cam 39 from the recess in the cradle.

Alignment of the cam surfaces of the upper and lower cams may be accomplished first by endwise adjustment of the lower cam bar C, by moving it endwise in the bracket and tightening it in adjusted position and a finer further adjustment of alignment by manipulation of the spindle bolt 32 against the cams in the recess 16 of the upper former bar B. It will thus be noted that a fine adjustment may be made be-

tween the cams and the apices of the cam shoes to assure accuracy of cut of the work piece.

It is to be understood that the cam arrangement of the present invention may also be applied to the back arm of a lathe carriage.

The springs 46 are loaded by the bolts 47 and 48 to maintain the desired floating pressure on the shoes 59 and 60 and the follower cam 39 is contoured so that this pressure is not appreciably changed as the shoe 59 rides over the high and low points of the cam faces 22. As a result the shoes have accurate riding engagement or operative clearance relation at all times with the cams without exerting excessive frictional wear on the cams. In addition the yielding mounting for the follower cam absorbs any changes in distance between the apices of the shoes. This invention has increased the tolerance accuracy of lathes on which it has been introduced from .001 inch to .0001 inch.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In combination with a profile turning lathe having a rocking carriage, a first cam mounted on the lathe alongside the path of movement of the carriage for controlling rocking of the carriage, a first cam follower carried by the carriage and riding on said first cam, a second cam follower carried by the carriage, and a resiliently mounted follower cam having a shape complementing the shape of the first cam and coacting with said second cam follower to maintain accurate riding contact between the first follower and first cam.

2. In combination with a profile turning lathe having a rocking carriage with a laterally extending rock arm, first and second opposed cam followers transversely pivoted on said arm, a cam support on said lathe, a first cam carried by said cam support and coacting with the first cam follower to control rocking of the carriage, a second cam complementary with said first cam coacting with the second cam follower, and a resiliently yieldable mounting for the second cam for maintaining accurate riding of the first follower on the first cam.

3. In combination with a lathe having a rocking tool carriage, means for controlling the rocking movement of said tool carriage comprising a bracket, upper and lower former bars removably mounted on the bracket, said carriage having an arm extending between said former bars, opposed cam followers pivoted on said arm, cam means in the upper former bar arranged to be engaged by one of the cam followers, cam means in the lower former bar arranged to be engaged by the other of said cam followers, and a spring mounting for the cam means in the lower former bar to cause positive contact of the cam follower with the cam in the upper former bar without undue friction, said cam means in the lower former bar having surfaces complementing the surfaces of the cam means in the upper former bar to minimize movement of the spring mounting as the cam followers advance over the surfaces.

4. Means for controlling the rocking movement of a tool carriage in a lathe comprising a bracket, former bars mounted in said bracket, a first cam adjustably fixed in one former bar, a second cam

complementary to said first cam and resiliently mounted in the other former bar, said tool carriage having an arm extending between the cams, opposed cam follower shoes pivotally mounted on the end of said arm and respectively having simultaneous line contact with the first and second cams, said cam follower shoes having relative movement as said arm oscillates, the resilient mounting of the second cam maintaining positive engagement of the one cam shoe with its cam regardless of the relative positions of the shoes and regardless of any variation in the vertical distance between the centers of pivotal connections of the shoes to the arm, and said complementary

shape of the second cam minimizing movement of the resilient mounting as the cam shoes advance over the cam surfaces.

JULIUS E. SHAFER.
